BAG SEAL

Allan A. Norin, Chicago, Ill., assignor to Porter Safety Seal Company, Chicago, Ill., a corporation of Illinois

Filed June 24, 1958, Ser. No. 744,137

6 Claims. (Cl. 292—308)

The invention relates to bag seal improvements and particularly of that type provided with a cord arranged to encircle a gathered neck of a bag and to be securely locked in place with a deformable lead seal body.

Bag seals of the type here under consideration have found extensive use in post offices, banks, shipping companies, and other organizations wherein bags are used to store and ship articles of value and the like. The advantage of this type of seal is that it inhibits unauthorized access to the bag contents.

It will be understood by those skilled in the art that when such bag seals of the type here considered are used, the bag is first "necked down" and the tie cord loops provided on the seal are arranged to encircle the bag, and then the seal element itself is used to pull the loops into a tight constriction about the bag neck. At this point, a deformable body associated with the seal is squeezed in an appropriate tool, which locks the bag and tie cord in bag-closed position. Of course, after transport of the particular bag, the seal must be removed; and the only convenient way to accomplish same is to cut the tie cord. Experience has shown that in removing the seal from the bag, the bag is frequently cut or gashed, thereby destroying the future usefulness of the bag per se. This, of course, is undesirable especially in view of the fact that there is a large disparity between the cost of the bag and the relatively inexpensive seal.

It is, therefore, a primary object of this invention to provide an improved bag sealing arrangement.

It is another object of the invention to provide a bag seal arrangement of the type here under consideration, having a combination of deformable sealing elements and a relative non-deformable bag engaging element formed and arranged to cooperate and provide improved bag sealing characteristics.

It is a specific object of the invention to provide the combination indicated above, having structure to guide any cutting action and so localize same as to eliminate any possibility of the bag being gashed or otherwise damaged.

It is a further specific object of the invention to provide with the combination above, a tie cord arrangement designed to facilitate seal removal.

Still another specific object of the invention is to provide an arrangement including a bag-engaging element which accommodates cutting of the tie cords from either side without turning the bag more than 90° and thereby reducing the time required to open the bags.

Yet a further object of the invention is to provide in an arrangement of the type described a flexible bag-engaging element which, upon mounting of the bag, will produce a pinch effect on the bag and avoid seal slippage relative to the bag.

Still another object of the invention is to provide in the bag-engaging element, elongated tie cord receiving slots which permit the application of the seal arrangement to bags of varying sizes.

These and other objects of the invention will become apparent in the course of the following description, and

2

from an examination of the associated drawings, wherein:

Figure 1 is a plan view of the seal arrangement hereunder consideration,

Figure 2 is a perspective view of the non-deformable element used in the seal combination, and particularly showing the front portion thereof,

Figure 2a is another perspective view of the non-deformable element, and illustrating the rear portion thereof,

10 Figure 3 is a fragmentary perspective view illustrating the seal arrangement in combination with a bag, and

Figure 4 is a front elevational view of a slightly modified embodiment of the non-deformable element incorporated in the arrangement.

15 Describing the arrangement in detail, and directing attention first to Figure 1, it will be understood that a deformable body is indicated generally at 2 and may be composed of lead or other suitable material. The body 2 in its original form is generally planar, and is provided

20 with a plurality (preferably, four) holes or apertures 6, 6 extending therethrough. It will be noted that the holes 6 are generally parallel to each other and also parallel to the general plane of the deformable body 2. A pliant tying cord indicated generally at 8 is threaded through,

25 in series, the outer holes 6 on the left and right of the deformable element 2, and thereafter in series through the inner holes 6 of said deformable element. With the pliant tie cord 8 threaded through the deformable element in this manner, it forms a pair of generally parallel

30 inner and outer loops 10 and 12. Those skilled in the art will understand that the loops 10 and 12 encircle the neck of the bag, as hereinafter described more in detail.

Intermediate the loops 10 and 12 and deformable element 2, a relatively rigid non-deformable element indicated generally at 14 is provided.

35 Turning to Figures 2 and 2a, it will be noted that the element 14 comprises a forward wall indicated generally at 16 and a rear wall indicated generally at 18. The rear wall 18 is composed of two oppositely extending wing portions

40 20, 20. Said wing portions 20 are generally planar and each having provided therein an open ended aperture 22. The front wall 16 is also provided with oppositely extending wing portions 24, 24 said wing portions 24 extending outwardly further than the adjacent wing portions 20

45 of the rear wall 18. It will also be noted that in the preferred form of the invention, the wing portions 24 are angularly related to each other and arranged to converge centrally of the non-deformable element 14. Each of the wing portions 24 is further provided with a closed, elongated slot 26, 26, the purpose of all of said slots being

50 hereinafter described more in detail.

In a preferred embodiment of the invention, the front wall 16 and rear wall 18 are integrally formed so that the adjacent wing portions 20 and 24 of the respective

55 walls each form a rigid non-deformable guiding slot 30. The guiding slots 30, of course, have their outer ends open and are desirably arranged to receive and guide a cutting edge, such as a knife, without the knife inadvertently slipping from said slot. The advantage of this structure will hereinafter be explained in detail.

60 Turning now in Figure 3, which illustrates a preferred embodiment of the invention here under consideration in sealing or locking arrangement and in combination with a bag 34, it will be noted that the bag 34 has been necked down as at 36, whereat the tie cord loops 10 and 12 have been arranged to encircle the necked-down bag portion 36 and the tie cord 8 has been pulled tightly, whereby the loops 10 and 12 constrictively surround said bag neck. In this position, the relatively rigid non-

65 deformable element 14, and particularly the wings 24, 24 thereof, firmly abut and engage the bag neck 36; and a central portion 40 of the deformable element 2 is in

tight abutting relation with an adjacent central portion of the rear wall 18, and body 2 has in effect been deformed to tightly lock the arrangement in position.

Those familiar with the art will understand that once the sealing arrangement has been pulled into position on a bag neck and before body deformation, the tie cord 8 is extremely tight throughout its entire operative length. When the body 2 is deformed, the portion of the tie cord 8 within the body tends to increase in length. This, of course, puts more tension on the loop portions 10 and 12. It is therefore desirable that the wing portions 24 of the front wall 26 be resiliently deflectable so that upon final deformation of the body 2, the wing portions 24 are urged to springingly engage the adjacent bag neck.

It will be readily apparent from the structure shown in Figure 3 that the slots 30, 30 formed in the non-deformable element 14 provide clear and open cutting slots to receive any appropriate cutting edge, such as a knife. It is also apparent that the wing portions 20 and 24 which define each slot 30 effectively guide any cutting action to avoid contact between the bag and the cutting instrument. The abutting flat contact between the deformable element and the flat rear portion of the rear wall 18 prevents the deformable element 2 from accidentally closing the slots 30 upon original deformation. It will also be apparent that the apertures 22 in the wing portions 20 and the slots 26 in the wing portions 24 are so aligned that a strand of each loop 10 and 12 is presented in each slot 30 for cutting (see Figure 1). It is, therefore, only necessary to place a cutting instrument in only one of the slots 30, whichever may be convenient in a given bag installation. Of course, with the single cut, the entire sealing arrangement becomes disassociated with the bag.

Turning to Figure 4 which illustrates a slightly modified arrangement of the non-deformable element 14, it will be noted that front wing portions 24a are slightly spaced from each other at the center portion of the element. In addition, upper and lower forwardly projecting flanges or ledges 44 are also provided on the wing portions 24a. When a non-deformable element as here illustrated is utilized in combination with the deformable element and tie cord illustrated in Figure 1, it will be readily apparent that the ledges 44 tend to tightly grip the adjacent bag neck and that the space 46 between

the wing portions 24a will receive a portion of the adjacent bag during assembly, and thereby aid in the spring action of the deflectable wing portions 24a as above described.

It will thus be understood that I have provided a unique seal having, in combination, deformable body element and a relatively non-deformable body element formed and arranged to offer improved bag seal and ready disassembly from a locked bag.

10 The invention as shown is by way of illustration and not limitation, and may be modified without departing from the spirit thereof or the scope of the appended claims.

What is claimed is:

15 1. As an article of manufacture, a bag gripping element adapted to be associated with a deformable locking body and a bag encircling cord; said element including a rear wall having a planar surface arranged to engage said body, said rear wall forming oppositely extending first wings, a front wall having oppositely extending second wings in acute angular relation with said first wings and said second wings defining a pair of opposed generally U-shaped cutting slots exposing portions of said cord.

20 2. An article according to claim 1, having apertures in said first wings which are open ended slots and apertures in said second wings which are closed slots.

25 3. An article according to claim 1, wherein said second wings are provided with adjacent ends located centrally of said rear wall as seen in plan view.

30 4. An article according to claim 3, wherein said adjacent ends of said second wings define a small aperture therebetween, said second wings having forwardly extending gripping flanges along opposite edges as seen therein in elevational view.

35 5. An article according to claim 1 wherein said second wings are resiliently deflectable.

40 6. An article according to claim 1 wherein said second wings are provided with forwardly extending gripping flanges.
